UNITED STATES PATENT OFFICE.

ELMER E. HAUER, OF SPRINGFIELD, OHIO, ASSIGNOR TO THE LAGONDA MANUFACTURING COMPANY, OF SPRINGFIELD, OHIO, A CORPORATION OF OHIO.

ROTARY MOTOR.

1,124,613.

Specification of Letters Patent. Patented Jan. 12, 1915.

Application filed May 22, 1914. Serial No. 840,338.

To all whom it may concern:

Be it known that I, ELMER E. HAUER, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors and more particularly to a motor for driving tube cleaners that is adapted to travel through a tube with the cleaner, although it may be used for other purposes.

15 The object of my invention is to provide a simple and efficient motor of great stability that will withstand the hard service of driving tube cleaning apparatus and with that end in view I form the main frame or 20 body with an outer and inner cylinder integrally with a supply head. This gives a rigid, stable and durable structure in which the parts are not liable to jar loose.

25 With these and other objects in view my invention consists of the constructions and combinations hereinafter described and set forth in the claims.

30 In the accompanying drawings which form a part of this specification Figure 1 is a longitudinal section of a motor embodying my invention. Figs. 2 and 3 are cross-sections on the lines 2—2 and 3—3 respectively of Fig. 1 and Fig. 4 is a longitudinal section showing some modifications.

35 Like numerals represent the same parts in the several views.

40 In the drawings 1 represents a supply head having forwardly projecting cylinders 2 and 3, the inner cylinder 3 having a cross-partition 4, said head, cylinders and partition being formed integrally as shown. The inlet 5 of the supply head opens into the inner cylinder 3 and an opening 6 through the longitudinal wall of said cylinder admits the motive agent to an annular chamber 7 formed between the cylinders 2 and 3. The inner cylinder 3 is shorter than the outer cylinder 2 and the bore of that portion of the outer cylinder which extends 45 beyond the inner cylinder is enlarged forming a shoulder or inclined off-set 8. A ported partition 9 may be secured in any suitable way to form the front wall of the annular chamber 7; but is shown as having 50 inclined outer walls seated against the off-

set 8 and tightened in place by being screw-threaded at 10 to the inner cylinder.

55 A rotary motor member 11 which is shown in the form of a turbine having buckets 12 operates within the motor chamber 13 formed by the enlarged forward portion of the outer cylinder 2 in front of the ported partition, the motive agent being supplied thereto through inclined ports 14 in the ported partition. The rotary motor member 60 is keyed to a shaft 15 by a key 16 and is tightened against a shoulder 17 by a nut 18 on the screw-threaded end 19 of said shaft, said screw-threaded end also forming the means of attaching the tool to be driven. 65 Said shaft is journaled within the inner cylinder 3 and a removable bushing 20 is preferably provided, which may be secured in any suitable way; but is shown as screw-threaded at 21 to the inner cylinder, cross-slots 22 in the forward end being provided for the engagement of a tool to screw it in place. A thrust plate 23 is seated against the cross-partition 4 and a flange 24 on the shaft extends between said plate and the 70 rear end of the bushing 20.

75 An inlet passage 25 through the cross-partition and thrust plate in line with a longitudinal passage 26 in the shaft admits the motive agent to the thrust bearing and 80 to the journal bearing through cross passages 27 and discharges through the cross passage 28, thus affording a constant flow of the motive agent for lubrication; and as an additional aid for this purpose an 85 annular chamber 29 is formed between the shaft and bushing.

90 The supply head is screw-threaded at 30 for the attachment of a supply conduit and a removable strainer 31 soldered to a ring 32 having screw-threads of like pitch with the threads 30 is seated against a shoulder 33 in the head.

95 Some modifications shown in Fig. 4 will now be described. An anti-friction thrust bearing is interposed between the thrust plate 23^a and shaft flange 24^a, said bearing being shown as comprising two rings 34 each having oppositely disposed hemispherical recesses opening through the outer 100 walls so that when the rings are riveted together by rivets 35 with balls 36 in the recesses, the balls will project slightly beyond the outside wall of said rings and contact with the thrust plate 23^a and the shaft 105 110

flange 24^a. Another modification consists in omitting the lubrication passages through the shaft and providing the bushing with a channel 37 and the shaft 15^a with a recess 38. The motive agent is admitted by a passage 25^a through the cross-partition 4^a and thrust plate 23^a to the anti-friction bearing and passes around the shaft flange 24^a into the channel 37 and is discharged in front of the bearing, the motive agent in its passage being more thoroughly distributed by the recess 38 in the shaft. A further modification is shown in that the rotary motor member 11^a is provided with a shroud 39.

Having thus described my invention I claim:

1. In a rotary motor, a supply head having two forwardly projecting cylinders 20 formed integrally therewith, one of said cylinders being disposed within the other forming an annular chamber between said cylinders, the longitudinal walls of the inner cylinder having an opening there- 25 through to admit the motive agent to said annular chamber, a ported partition introduced through the front end of the outer cylinder and secured in place to form the front wall of said annular chamber and a 30 rotary motor member in front of said ported partition having a shaft journaled within said inner cylinder, substantially as described.

2. In a rotary motor, a supply head having 35 two forwardly projecting cylinders formed integrally therewith, one of said cylinders being disposed within the other forming an annular chamber between said cylinders, the longitudinal wall of the inner cylinder 40 having an opening therethrough to admit the motive agent to said annular chamber, a cross-partition in front of said opening, a ported partition introduced through the front end of said outer cylinder and secured 45 in place to form the front wall of said annular chamber, a rotary motor member in front of said ported partition having a shaft journaled within said inner cylinder in front of said cross-partition and means to 50 take the thrust of said member, substantially as described.

3. In a rotary motor, a supply head having two forwardly projecting cylinders formed integrally therewith, one of said 55 cylinders being disposed within the other forming an annular chamber between said cylinders, the inner cylinder having a cross-partition and the longitudinal walls of said cylinder having an opening there- 60 through in the rear of said cross-partition to admit the motive agent to said annular chamber, a bushing secured within the inner cylinder in front of said cross-partition, a ported partition introduced through the 65 front end of the outer cylinder and secured

in place to form the front wall of said annular chamber, a rotary motor member in front of said ported partition having a shaft journaled in said bushing, said shaft having a flange at its rear end in front of said cross-partition, substantially as described.

4. In a rotary motor, a supply head having two forwardly projecting cylinders forming an annular chamber between the said cylinders, the inner cylinder being of 75 less length than the outer cylinder and the bore of the outer cylinder being enlarged at its forward end forming an off-set, said cylinders being formed integrally with said head, a ported partition introduced through 80 the forward end of said outer cylinder and screw-threaded to said inner cylinder to tighten the same in place against said off-set, a rotary motor member in front of said partition within the enlarged bore of said 85 outer cylinder and having a shaft journaled within said inner cylinder, substantially as described.

5. In a rotary motor, a supply head having two forwardly projecting cylinders 90 forming an annular chamber between said cylinders, said cylinders being formed integrally with said head, the inner cylinder being of less length than the outer cylinder with a partition across its bore intermediate its length and an opening through said walls in the rear of said partition to admit the motive agent from said supply head to said annular chamber, the bore of the outer cylinder being enlarged at its front end 100 forming an off-set, a ported partition introduced through the front end of the outer cylinder and screw-threaded to said inner cylinder to tighten and hold the same in place against said off-set, a rotary motor 105 member in front of said ported partition within the enlarged bore of said outer cylinder and having a shaft journaled within said inner cylinder, substantially as described.

6. In a rotary motor, an inner and outer cylinder and a supply head having a central supply passage extending into the inner cylinder and opening through the wall of said cylinder into an annular chamber 115 formed between said inner and outer cylinders, said cylinders being formed integrally with said head, the inner cylinder being of less length than the outer cylinder and having a cross-partition in front of 120 said wall opening, the bore of the outer cylinder being enlarged in its front portion forming an off-set, a ported partition introduced through the front end of said outer cylinder and tightened in place 125 against said off-set, a rotary motor member in front of said partition within the enlarged bore of said outer cylinder and having a shaft journaled within the inner cylinder in front of said cross-partition and 130

means to admit the motive agent to the bearing of said shaft, substantially as described.

7. In a rotary motor, a supply head having two forwardly projecting cylinders forming an annular chamber between said cylinders, the inner cylinder being of less length than the outer cylinder and the outer cylinder having an inclined off-set within 10 its bore, a ported partition screw-threaded to the inner cylinder and having inclined walls seated against said off-set and a rotary motor member in front of said ported partition having a shaft journaled within said 15 inner cylinder, substantially as described.

8. In a rotary motor, a supply head with a forwardly projecting cylinder of less diameter having a cross-partition therein, said head, cylinder and partition being 20 formed integrally, the longitudinal wall of said cylinder having an opening therethrough in the rear of said partition for the passage of the motive agent, a bushing in 25 said cylinder, a rotary motor member having a rearwardly extending shaft journaled in said bushing, said shaft having an integral flange and a thrust bearing between said flange and cross-partition, substantially as described.

9. In a rotary motor, a supply head with a forwardly projecting cylinder of less diameter having a cross-partition, said head, cylinder and partition being formed integrally, the longitudinal wall of said cylinder having an opening therethrough in 35 the rear of said cross-partition for the passage of the motive agent, a shaft bearing in said cylinder, a rotary motor member hav-

ing a rearwardly extending shaft journaled in said bearing and means to supply a constant flow of the motive agent to the bearing surface of said bearing and discharge the same in front of said bearing, substantially as described.

10. In a rotary motor, a supply head with a forwardly projecting cylinder of less diameter having a cross-partition and a rotary motor member having a rearwardly extending shaft journaled in said cylinder, said cross-partition having an inlet and said 50 shaft having openings to admit the motive agent to the bearing of said shaft and discharge the same in front of said bearing, substantially as described.

11. In a rotary motor, a supply head having two forwardly projecting cylinders forming an annular chamber between said cylinders, said cylinders being formed integrally with said head, said inner cylinder 60 having an opening through its longitudinal wall to admit the motive agent from said supply head to said annular chamber, a cross-partition in said inner cylinder in front of said opening, a rotary motor member having a shaft journaled within said 65 inner cylinder in front of said partition and a removable strainer in said supply head, substantially as described.

In testimony whereof I have hereunto affixed my signature in the presence of two 70 witnesses.

ELMER E. HAUER.
